UNITED STATES PATENT OFFICE

FREDERIC W. BUTT, OF BROOKLYN, AND ALEXANDER MCGARY, OF NEW YORK, N. Y.

VENTILATOR

Application filed March 31, 1926. Serial No. 98,676.

This invention relates to improvements in ventilators and methods of ventilation, for movable enclosures, such as railway cars or other vehicles.

5 The invention embodies means for creating through a ventilator opening, a draft of air of a velocity substantially dependent upon the vehicle speed of travel, such opening being provided with a closure device controlled by

10 the draft of air in a manner to efficiently maintain the desired ventilation. According to this invention a dependable and relatively simple, inexpensive construction is provided for the intended purposes.

15 Further and more specific objects, features and advantages will more clearly appear from the detailed description given below taken with the accompanying drawings which form a part of this specification.

20 In the drawings, Fig. 1 illustrates in cross-sectional elevation, a portion of a railway car equipped with the ventilator embodying this invention.

Fig. 2 is a plan view, partly in section, of 25 the same device as shown in Fig. 1.

Fig. 3 is a sectional view taken substantially along the line 3—3 of Fig. 1.

Fig. 4 is an enlarged view showing in detail a form of rotatable closure member which 30 may form a part of the installation as shown in Fig. 1, and

Fig. 5 is a sectional view taken substantially along the line 5—5 of Fig. 4.

In Fig. 1 the "shoulder portion" of the 35 roof of a well known type of railway passenger car is illustrated. This portion includes an outer vertical side wall portion 10 and an inner wall portion 11. In the construction of the cars the usual provision is first made through each of these walls for 40 ventilator openings. The inner wall 11 is provided with a ventilator opening 12, which may be closed, when no ventilation is required, by a tiltable shutter 13 pivotally mounted as at 14. This shutter is operable by the usual window hook or pole applied to an eyelet 15. The position of this shutter when closed is indicated by the dotted lines.

The outer wall 10 may be formed with a 45 suitable opening at the exterior of which a

suitable draft creating device may be installed; for example, in the construction shown this device may comprise a sheet metal hood 16 having a downwardly and outwardly directed opening 17. The sheet metal of this hood is bent inwardly and downwardly along the sides of the opening 17 to provide flanges 18 which, together with the other parts of the hood, are shaped in a manner to create an outward draft of air through the ventilator responsive to movements of the railway car in either direction along the railroad track. This draft of air exhausting from the interior of the railway car will be of a velocity substantially dependent upon the vehicle speed of travel, the draft tending to materially increase at the higher speeds of travel, whereas when the vehicle is at rest or substantially at rest, relatively little draft is created through the ventilator.

At the inner side of the opening through the wall 10 a plate member 19 may be secured and is formed with a central apertured portion surrounded by a circular flange 20. Within the flange 20 a number of openings may be provided through the plate 19. In the particular construction shown, two complementary or concentric sector shaped openings 21 and 22 are formed. Plate 19, except for the sector openings 21 and 22, substantially closes off the ventilator opening through the wall 10.

At the apices of the complementary sector shaped openings a rotatable closure member 23 may be mounted upon a shaft 24, which shaft is preferably fixed to the plate 19. The closure member may be removably retained upon the shaft 24 by a suitable cotter pin 25 or other desired means, and preferably may comprise a plurality of complementary or concentric sector shaped plates integrally formed with or welded to a hub portion 26 which receives the shaft 24. With the device as shown, the closure member has two wing portions or sector plates 27 and 28 corresponding respectively to the sector shaped openings 21 and 22. When the ventilator is in closed condition, the plates 27 and 28 are brought into registration with the openings 21 and 22 and when the ventilator is in its

fully opened condition, as shown in the drawings, the closure member 23 is turned to a position substantially 90° from its closed position.

- 5 In order to limit the rotational movement of the closure member, a suitable stop pin 29 may be mounted upon the plate member 27 for engagement with either of two stop pins 30 and 31. The stop pins 30 and 31 may be 10 fixed upon the circular flange 20 and respectively serve to limit the closing and opening movements of the closure member.

The sector plate members 27 and 28 may be of like construction, and in the form shown, 15 they are provided with radially extending corrugations as at 32, one side wall of each corrugation being preferably formed with a plurality of perforations as at 33, whereas the opposite side walls of the corrugations 20 are without perforations. The corrugations of the sector plates serve as strengthening means, and the perforations fulfill a further purpose hereinafter described. Along one edge of each of the sector plate members a 25 radially extending integral propeller blade is formed as shown at 34. At the edges of the plate members the corrugations may terminate in peripheral and edge flanges or members as 35 which serve to stiffen the 30 plate members, preventing the passage of air over the peripheral edge of corrugated area and make possible a finished appearance.

The rotatable closure member is preferably so balanced that it will normally be maintained by gravity in the open position. Accordingly, when the railway car or vehicle is at rest, the ventilator will normally be maintained in open condition, thus providing ample ventilation. When the vehicle assumes a substantial speed, then the air exhausting hood 16 would normally tend to withdraw air from the vehicle, producing a lower pressure on the outside of the ventilator than on the inside thereof. Heretofore 40 this has resulted in excess ventilation at high speeds and a consequent waste of heated air, unless the ventilator is kept so nearly closed that insufficient ventilation will be provided when the vehicle is at rest or traveling 45 at a low speed.

With the present invention, however, as the vehicle gains speed, the increasing draft through the ventilator opening or increasing difference in pressure on opposite sides of the 55 ventilator will act upon the propeller blades 34 and the perforated corrugated areas of the rotatable member and cause the same to turn toward its closed position. The action of the draft of air upon the propeller blades will be 60 sufficient to initiate the closing movement, but under ordinary circumstances the propeller blades alone will be ineffective to cause the rotatable member to completely close. Therefore, in order to supplement the action 65 of the propeller blade portions, the perfora-

tions 33 are provided. These perforations cause the force exerted against the two sides of each of the corrugations 32 to be unbalanced and biased in a direction tending to move the rotatable member to closed position. Therefore, with the action of the propeller blade supplemented by the perforated corrugations, the rotatable member will be brought into substantial registration with the ventilator openings when the vehicle is 75 traveling rapidly. At such times the perforations 33 will provide the desired small amount of ventilation.

It will be noted that the rotatable member is mounted to be rotatable in a vertical plane 80 substantially parallel to the directions of travel of the car or vehicle but substantially perpendicular to the general direction of movement of the air currents therethrough. Accordingly, the rotatable member is restrained from movement in response to rocking or side to side motions of the vehicle. Therefore, transverse movements of the vehicle will have substantially no effect upon the operation of the ventilator. On the other hand, any jarring movements longitudinally 85 of the vehicle will serve to assist the draft of air in overcoming frictional resistance in the device as it assumes its proper position for the particular vehicle speed. Therefore, regardless of the normal vehicle movements, the ventilator will readily maintain the desired ventilation at various vehicle speeds. Furthermore, the desired uniform ventilation may thus be maintained in a railway car 90 whether the car moves forward or backward. The ventilator tends to maintain an approximately constant volume of air discharge at the various vehicle speeds, and since the ventilator shutter member has at least some inertia and extends in a direction generally perpendicular to the direction of movement of the main air current through the ventilator, the shutter member is not easily forced 95 out of proper position by sudden puffs of air 100 as of course occur adjacent railroad cars, particularly when passing other trains or bridge abutments, etc.

While we have described our improvements in great detail and with respect to a preferred form thereof, we do not desire to be limited to such form or details since many changes and modifications may be made and the improvements embodied in widely different forms, without departing from the spirit and 115 scope of the invention in its broader aspects; hence, we desire to cover all modifications and forms coming within the language or scope of any one or more of the appended 120 claims.

What we claim as new and desire to secure by Letters Patent is:

1. A ventilator comprising concentric sector shaped openings through the wall of the enclosure to be ventilated, and a closure 125

therefor comprising concentric sector plates rotatably mounted at the apices of said openings, said plates being formed with radial strengthening corrugations, terminating in

5 a peripheral flange.

2. A ventilator comprising concentric sector shaped openings through the wall of the enclosure to be ventilated, and a closure therefor comprising concentric sector plates 10 rotatably mounted at the apices of said openings, said plates being formed with radial corrugations, the side walls of certain corrugations being perforated whereby air drafts against the plates produce a turning movement for bringing the plates into full registration with the openings.

3. A draft controlled ventilator closure comprising rotatably mounted concentric sector plates, one edge of each plate being integrally formed with a radially extending propeller blade, said plates also being formed with radial corrugations, each corrugation having one side wall perforated for unbalancing the force of air currents against the 25 two opposite wall areas of the corrugation whereby strong air drafts against the plates produce a turning movement for bringing the closure into full registration with an opening of corresponding shape.

30 4. A draft controlled ventilator closure comprising rotatably mounted concentric sector plates radially corrugated, the corrugations being formed with means producing a turning movement responsive to strong air 35 drafts against the same.

5. In combination with an enclosed vehicle having a ventilator opening, means for creating through said opening a draft of air of a velocity substantially dependent 40 upon the vehicle speed of travel, and a closure device at said opening controlled by said draft of air, said closure device having propeller means for initiating its closing action, and additional means cooperating with the 45 draft of air to move the device to its fully closed position in response to strong air drafts through the opening.

6. A draft controlled ventilator closure comprising a rotatably mounted plate formed 50 with depressions in its surface, perforations being formed through the plate at said depressions whereby air drafts against the plate produce a turning moment of force tending to rotate the closure toward its closed position.

55 7. A ventilator construction comprising a plurality of openings through the wall of the enclosure to be ventilated, and a closure member therefor comprising a rotatably mounted 60 plate member having portions for covering each of said openings, said plate member being rotatable on an axis perpendicular to the wall adjacent said openings, each of said plate portions being formed with strengthening corrugations extending in a generally

radial direction and terminating at their outer edges in flanges extending transversely of said corrugations and in a generally peripheral direction.

8. A ventilator construction in which an 70 opening is provided through the wall of the enclosure to be ventilated, and a closure for said opening comprising a plate member rotatably mounted in a plane parallel to that of the wall and on an axis adjacent said opening, said axis being perpendicular to the wall, said plate being formed with strengthening corrugations extending in a generally radial direction, terminating in a peripheral flange.

80 9. A ventilator construction in which an opening is provided through the wall of the enclosure to be ventilated, and a closure for said opening comprising a plate member rotatably mounted in a plane parallel to that of the wall and on an axis adjacent said opening, said axis being perpendicular to the wall, said plate being formed with strengthening corrugations extending in a generally radial direction, terminating in a peripheral flange, 85 the side walls of one or more of said corrugations being perforated whereby air drafts against the same produce a turning movement for bringing the closure into registration with the opening.

90 In testimony whereof we have signed our names to this specification.
